Primary Examiner — W. A. Teddy Falloway**CLAIM**

The ornamental design for a snow lion ornament as shown and described.

DESCRIPTION

FIG. 1 is a front elevational view of a snow lion ornament showing my new design;

FIG. 2 is a perspective view thereof;

FIG. 3 is a left side elevational view thereof;

FIG. 4 is an enlarged view of portion 4 shown in FIG. 1; FIG. 5 is an enlarged view of portion 5 shown in FIGS. 2; and,

FIG. 6 is an enlarged view of portion 6 shown in FIG. 3. The dash-dot broken lines in the drawings depict portions of the snow lion ornament that form no part of the claimed design. The dot-dash-dot broken lines depict boundaries of the enlarged portions that form no part of the claimed design.
